DESIGN FOR A SIGNAL CHIME

Edward Matousek, Berwyn, Ill., assignor to Associated Electric Laboratories, Inc., Chicago, Ill., a corporation of Delaware

Application June 5, 1935, Serial No. 57,144

Term of patent 14 years

To all whom it may concern:

Be it known that I, Edward Matousek, a citizen of the United States of America, residing at Berwyn, Cook County, Illinois, have invented a new, original, and ornamental Design for a Signal Chime, of which the following is a specification, reference being had to the accompanying drawing, forming a part thereof.

The figure is a perspective view of a signal chime, showing my new design.

I claim:

The ornamental design for a signal chime, as shown.

EDWARD MATOUSEK.
